DESIGN FOR A KNITTED FABRIC.

SPECIFICATION forming part of Design No. 19,096, dated May 14, 1889.

Application filed April 12, 1889. Serial No. 307,032. Term of patent 7 years.

o all whom it may concern:

Be it known that I, GEORGE D. KINSEY, of Brooklyn, in the county of Kings and State of New York, have invented and produced a new and original Design for Knitted Fabrics, of which the following is a specification.

The accompanying drawing illustrates a design embodying my invention, the design being shown in the black portions of the figure.

The design consists, essentially, of substantially-parallel straight lines A near the edges of the design, from which extend inwardly and

alternately from opposite edges portions a, resembling protuberances upon the lines A. Intermediate of the lines A is a serpentine figure, B, and extending lengthwise through the serpentine figure is a straight line, C. 15

What I claim as my design is—

The design for knitted fabrics, substantially as herein shown and set forth.

GEORGE D. KINSEY.
